[57] CLAIM

The ornamental design for a fly casting reel, as shown and described.

DESCRIPTION

FIG. 1 is a perspective view of a fly casting reel, showing my new design;

FIG. 2 is a top plan view thereof;

FIG. 3 is a bottom plan view thereof;

FIG. 4 is a left side elevational view thereof;

FIG. 5 is a front elevational view, the rear being a mirror image thereof; and

FIG. 6 is a right side elevational view thereof.
